NEW YORK.

DRAFT-RIGGING FOR RAILWAY-CARS.

1,300,457.

Specification of Letters Patent. Patented Apr. 15, 1919.

Application filed July 26, 1916. Serial No. 111,364.

To all whom it may concern:

Be it known that I, JOHN F. O'CONNOR, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying drawings, 10 forming a part of this specification.

My invention relates to improvements in draft rigging for railway cars.

One of the objects of my invention is to provide a strong and efficient draft rigging. 15 A further object is to provide a compound key tandem gear dispensing with the usual side plates, to provide stops for the gear. Further objects will appear from the description of the device herein following.

20 In the drawings forming a part of this specification, Figure 1 is a side elevation, partly in vertical, longitudinal section of a draft rigging embodying my invention. Fig. 2 is a horizontal section taken on line 2—2 25 of Fig. 1. Fig. 3 is a cross section taken on line 3—3 of Fig. 1. And Fig. 4 is a rear end view of the spring cage which forms a part of the draft rigging shown.

Referring to the drawings, the numerals 30 5—5 indicate draft members or parts of the car under-frame to which the draft rigging is applied. 6 indicates a tie plate secured to the draft sills by suitable means, as for instance, the bolts 7—7. This is designed to 35 support the draft rigging in its position between the sills. A draw bar is shown at 8 having the usual butt 9 and being provided with the transverse slot 10 therein. A spring cage 11 is mounted immediately back of the 40 draw bar, the same being provided at its forward end with a recess 12 to receive the butt 9 of the draw bar. The rear face of the recess 12 is formed by the plate 13 which is 45 preferably integral with the upper and lower walls 14 and 15, respectively, of the spring cage. The cage is open at both sides and the bottom member 15 thereof, which is adapted to rest upon the tie plate 6, is provided with lateral extensions 16—16 which are adapted 50 to support the inner and outer yokes 17 and 18, respectively, which are hereinafter more particularly described.

The rear end of the spring cage is crossed by the follower 19 which forms an abutment 55 between the front compression resisting unit

20 and the rear compression resisting unit 21. In the particular embodiment of my invention shown in the drawings, each of the compression resisting units comprises an outer spring 22 and an inner spring 23 nested 60 therein. The front compression resisting unit is mounted within the spring cage 11, being seated at its forward end against the plate 13 and at its rear end against the rear transverse portion 24 of the inner yoke 17. 65 The rear compression resisting member 21 is seated at its forward end against the follower 19 and at its rear end against the transverse member 25 of the outer yoke 18. The follower 19 and the rear member 25 of the 70 outer yoke 18 are each preferably provided with a boss 26 to hold the rear compression resisting member in its position within the outer yoke. The rear follower 19 is provided at its top and bottom with forwardly projected flanges 27—27 which surround the offset portions 28—28 at the rear end of the spring cage, the said follower, through its engagement with the spring cage, virtually forming the rear end thereof. The two yokes 75 17 and 18 are mounted in horizontal position between the draft members. The outer yoke 18 is a U-shaped strap slotted at its forward ends as indicated at 29—29, for the passage of the coupler key 30, likewise the limbs of 80 85 the inner yoke 17 which lie within the limbs of the outer yoke 18 are slotted near their forward ends as at 31—31, for the passage of the coupler key 30.

The coupler key 30 consists of a straight 90 key 32 that extends through the transverse slot 10 in the draw bar 8 and through the slots in the two yokes and passes at its ends through the slots 33 within the draft members, within which said key is stationary in 95 the action of the draft rigging. The coupler key 30 also includes a U-shaped key 34, the free ends of which are turned rearwardly, the same partially inclosing the straight key 32 and extending with the straight key 32 100 through the draw bar and through the limbs of the yoke by being free to move longitudinally in respect to the draft member, such freedom being accomplished in the illustration of my invention appearing in the 105 drawings by terminating the U-shaped key within the inner faces of the draft members.

On rearward movement of the draw bar, the same slides upon the coupler key 30, 110 forcing the spring cage rearwardly and com-

pressing the front compression resisting unit between the front member 13 of the spring cage and the transverse member 24 of the inner yoke, which is held against rearward movement by the coupler key 30. The rearwardly moving spring cage through its follower portion 19 compresses the rear compression resisting member 21 between it and the rear connecting member 25 of the outer yoke 18; the said outer yoke is held against rearward movement by the coupler key 30.

On forward movement of the draw bar, the U-shaped portion 34 of the compound key is drawn forwardly by the draw bar, the engagement between the draw bar and the U-shaped portion of the key being effected by the shoulders 35—35 provided near the ends of the transverse slot 10 in the draw bar 8. The forward moving U-shaped portion of the compound key draws both the outer and the inner yokes forwardly, the inner yoke compressing the front compression resisting unit between the transverse member 24 of the yoke and the front plate 13 of the spring cage, the spring cage being held against forward movement through its engagement at its forward end against the member 32 of the compound key, as indicated at the numerals 36—36 in Fig. 2 of the drawings. Simultaneously, with the forward movement of the inner yoke, the outer yoke is drawn forwardly by the U-shaped portion 34 of the compound coupler key compressing the rear compression resisting unit 21 between the rear follower member 19 of the spring cage and the forwardly moving rear connecting member 25 of the outer yoke 18.

It will thus be observed that my invention provides a draft gear in which a multiple of independent simultaneously operable compression resisting units may be employed in tandem or other similar arrangement. It will be further observed that side casting to provide stops for the draft gear may be disposed with and that the connection between the draft gear and the car may be effected through the use of a single compound key.

50 I claim:

1. In a draft rigging for railway cars, in combination, draft members, a stationary key extended between the draft members, a movable key associated with the stationary key, a pair of yokes, a spring cage associated with one of said yokes, a compression resisting unit for each of the yokes, the spring cage in movement in one direction, compressing each compression resisting unit against its yoke, the said yokes being held stationary by the keys and in movement of the compressing resisting units in the other direction, the same being held by the spring cage which is, in turn, held stationary by the stationary key, the yokes compressing the compressing

resisting units against the spring cage, the movable key being adapted to draw the yokes toward the stationary key.

2. In a draft rigging, draft members, a compression resisting unit mounted between the draft members, a compound key associated with the draft members, a draw bar slidably mounted on said key and a draft yoke, the compound key comprising a stationary portion and a movable portion, the movable portion moving forwardly to compress the compression resisting member between the yoke and the stationary key, the said key holding the yoke stationary on rearward movement of the draw bar to compress the compression resisting member between the draw bar and the yoke.

3. In a draft rigging for railway cars, draft members, a draw bar mounted between the draft members, a plurality of yokes, a compression resisting unit for each of said yokes, a compound key having a stationary portion mounted between the draft members and a movable portion to connect the yokes to the draw bar, a member associated with the stationary key to engage one end of each of the compression resisting members, one of the yokes engaging the other end of each of the compression resisting members, the draw bar sliding on the key in rearward movement and in forward movement drawing the movable portion of the key forwardly to give forward movement to the yokes.

4. In a draft rigging for railway cars, draft members, an inner and an outer horizontal yoke between the draft members, a compound key mounted between the draft members, a draw bar slidably mounted on said key, a spring cage, a compression resisting unit within the spring cage, the inner yoke engaging said compression resisting unit at one end, a compression resisting unit mounted between the rear end of the spring cage and the rear end of the outer yoke, the compound key having a stationary portion and a movable portion, the movable portion drawing the yokes forwardly on forward movement of the draw bar, the stationary key holding the spring cage against forward movement on forward movement of the draw bar, the key holding the yokes on rearward movement of the draw bar, the draw bar on said movement forcing the spring cage rearwardly and compressing the compression resisting unit.

5. In a draft rigging for railway cars, draft members, a draw bar, a compound key, a plurality of yokes connected by said key to the draw bar, the draw bar being slidably mounted on said key, the key having a movable portion adapted to move forwardly with the draw bar to draw the yokes forwardly and a stationary portion to hold said yokes against rear movement.

6. In a draft rigging for railway cars, draft members, a stationary key secured at its ends to the draft members, a U-shaped key slidingly mounted upon the stationary key, a draw bar slidingly mounted on said key, a yoke engaged to the movable key, the draw bar being provided with means to move the movable key in one direction, the stationary key holding the movable key and the yoke against movement in the other direction.

7. In a draft rigging for railway cars, draft members, a spring cage mounted between said members, compression resisting members within the spring cage, a yoke passing through said spring cage and engaging said compression resisting members between it and one end of the spring cage, an outer yoke inclosing the spring cage, a further compression resisting member mounted between the end of said outer yoke and the rear end of the spring cage, a compound coupler key, a draw bar slidingly mounted upon said key and adapted to engage the front end of the spring cage, the compound key having a stationary portion and a movable portion, the yokes being connected to said movable portion, the movable portion being adapted to be moved forwardly by the draw bar, the spring cage in forward movement of the draw bar being stopped by the stationary portion of the key.

8. In a draft rigging, draft members, a draw bar, a spring cage, compression resisting members within the cage, a yoke passing through the cage and adapted to compress the members therein, a compound key, a draw bar, the draw bar being slidingly mounted upon the key, the key having a stationary portion extending between the draft members and a movable portion adapted to be given movement in one direction by the draw bar, the spring cage being held against movement in one direction by the stationary portion of the key and adapted to be moved in the other direction by the draw bar.

9. In a draft rigging for railway cars, draft members, a spring cage mounted between the draft members, a key, a draw bar, a draft yoke and compression resisting members, the spring cage being provided at its forward end with a hollow hood to receive the draw bar and being stopped against forward movement by the key, the draw bar sliding on said key in rearward movement, the said key having a movable portion to draw the yoke forwardly on forward movement of the draw bar.

In witness that I claim the foregoing I have hereunto subscribed my name this 22nd day of July, 1916.

JOHN F. O'CONNOR.
